UNITED STATES PATENT OFFICE.

ARNOLD D. ALT, OF ST. LOUIS, MISSOURI.

APPARATUS FOR WASHING PHOTOGRAPHIC PRINTS.

974,336.

Specification of Letters Patent. Patented Nov. 1, 1910.

Application filed January 10, 1910. Serial No. 537,226.

To all whom it may concern:

Be it known that I, ARNOLD D. ALT, residing in the city of St. Louis and State of Missouri, have invented a new and useful Improvement in Apparatus for Washing Photographic Prints, of which the following is a full, clear, and exact specification, reference being had to the accompanying drawings, which form a part thereof.

10 My invention relates to apparatus whereby the washing which forms a part of the process of developing photographic and similar negatives and prints is done.

15 In developing photographic and similar negatives and prints, it is necessary that all the surplus or unused chemicals be removed and this is done by thoroughly washing said negatives and prints by exposing them to a stream of running water or by

20 leaving them for a length of time immersed in a bath of water. When a bath is used the negatives or prints are immersed therein and left until the water of the bath has done its work and then this water is drawn off

25 and fresh water supplied. The water of the bath is changed as often as may be necessary until the prints or negatives are thoroughly washed.

30 The object of my invention is to provide an apparatus for washing photographic and similar negatives and prints in which the water of the washing bath is supplied in measured quantities and is automatically drawn off at regular intervals without the

35 care or attention of an attendant.

40 My invention is fully shown in the accompanying drawings where similar reference letters are used to designate similar parts.

45 Figure 1 is a perspective view of one form of the apparatus; Fig. 2 is a view of a vertical section on the line 2—2 of Fig. 1, showing the working parts at one end of the apparatus; Fig. 3 is a view of a section on the line 3—3 of Fig. 2, showing the construction of a part of the apparatus; Fig. 4 is a view of a section on the line 4—4 of Fig. 2, showing a detail of construction; and Fig. 5 is a view showing a second form of construction of a part shown in the other figures.

50 Referring to the figures, A is a tank having suitable supports B; C is a funnel having an overflow pipe E and a pipe D through which water is discharged into the tank near the bottom thereof. The pipe D is fastened to the tank by means of the

holder M and has a valve F by means of which the flow of water from the funnel into the tank A is controlled.

55 G is a siphon having its shorter leg S terminating inside the tank and its longer leg T terminating outside of the tank. In its preferred form that part of the siphon G which is inside of the tank A is made oval as shown in Figs. 3 and 4, and the shorter axis 65 of the oval lies in a vertical plane at the upper part of the bend of the siphon. The shorter leg S of the siphon may terminate just above the bottom of the tank A as shown in Figs. 1, 2 and 4, or it may terminate in a depression P formed in the bottom 70 of the tank as shown in Fig. 5.

75 H is an opening in the side of the shorter leg S of the siphon through which air is admitted when the water falls below the level of this opening. When the siphon is operating and the water falls below the opening H air enters the siphon and causes it to cease to operate. Without the opening H the siphon would operate until the lower 80 end of the leg S was uncovered and then there would be a rush of water and air through the large opening in the end of the siphon, and this rush would tend to carry floating prints to the siphon. The opening 85 H is small as compared to the opening at the lower end of the leg S and the flow of water through this opening H is not rapid, so that when it is uncovered there is not 90 much tendency for the prints to be drawn against the siphon.

95 When the leg S of the siphon terminates in a depression formed in the bottom of the tank as shown in Fig. 5, I prefer to have the opening H placed so that it will be about level with the top of the depression P; when, however, the shorter leg S of the siphon terminates just above the bottom of the tank A as shown in Figs. 1, 2 and 4, I 100 prefer to have the opening H about half or three quarters of an inch above the bottom of the tank.

105 R is a screen placed in the tank from side to side thereof for the purpose of preventing light prints or negatives from floating against the siphon and interfering with its operation. The prints or negatives are placed in that part of the tank separated from the siphon by the screen R. I find that when the siphon G is placed close to the end of the tank and the lower part of the leg S is cut away at the rear as shown 110

in Fig. 4 the screen R may be dispensed with and this cut-away portion will prevent the negatives or prints from interfering with the operation of said siphon. When 5 this form of the leg S of the siphon is used the opening H should be placed on a level with the top of the cut-away portion K, as shown in Fig. 4.

N is a pipe leading from a source of supply of water through which water is admitted into the funnel C.

The operation of the device is as follows: The prints or negatives to be washed are placed in the tank and water is supplied to 10 the funnel C through the pipe N. The amount of water should be such that the funnel will be kept full to a height such that the water is just on the point of flowing out through the overflow pipe E. The flow of 15 water into the funnel is determined by the pipe N; and the flow of water from the funnel into the tank is controlled by the valve F and the height of the upper end of the overflow pipe E above the surface of the 20 water in the tank. When the water has accumulated in the tank to a height sufficient to cover the siphon G, the siphon will operate and the water will be drawn upward through the shorter leg S and discharged 25 through the longer leg T. The size of the siphon must always be such that the water will be discharged therethrough from the tank more rapidly than it is admitted through the pipe D, so that the tank will 30 be emptied by the operation of the siphon. I prefer to make the siphon of an oval cross section as shown in the figures, because when the tank is filled so that the water covers the lower part of the upper bend of 35 the siphon it will begin to leak or dribble over into the longer leg from the shorter leg, and when the distance between the lower part of the bend of the siphon and the upper part is small this dribbling or leaking of 40 water will not last a very long time. The dribbling or leaking will continue until the siphon has become completely immersed in the water, and then the siphon will begin to 45 operate normally. When the water has been 50 discharged from the tank so that its level has fallen to the opening H in the leg S, air will enter through said opening H and the siphon will cease to operate, and water will be left in the tank to a depth about the 55 distance of the opening H above the bottom of the tank. When the end of the leg S of the siphon is in the depression P as shown in Fig. 5, the water will be drawn completely from the tank with the exception of what 60 may remain in the depression P.

The rate of flow of the water into the tank may be regulated by the valve F. When the water flows into the tank slowly and the siphon G is large the tank will be filled 65 slowly and discharged rapidly, so that the

interval between one discharge and the next will be long. If the rate of flow of water into the tank from the funnel C be large as compared to the rate of discharge through the siphon G, the interval between one discharge and another will be short and the time required to discharge the tank will be comparatively long.

By properly adjusting the valve F and the supply of water to the funnel C the apparatus may be made to work so as to fill and discharge as desired, and when once adjusted it will continue to operate to supply water to wash the prints or negatives without any attention.

What I claim as new and desire to secure by Letters Patent, is:

1. An apparatus for washing photographic negatives and prints comprising a tank, a pipe for supplying water to said tank, a funnel at the upper end of said pipe, an overflow pipe leading from said funnel, a siphon adapted to discharge the water from said tank, and means whereby said negatives and prints are prevented from interfering with the operation of said siphon, substantially as described.

2. An apparatus for washing photographic negatives and prints comprising a tank, a pipe for supplying water to said tank, a funnel at the upper end of said pipe, an overflow pipe leading from said funnel, a valve for regulating the flow of water through the pipe for supplying water to said tank, a siphon adapted to discharge the water from said tank, said siphon having an opening in its shorter leg above the lower end thereof, and means whereby said negatives and prints are prevented from interfering with the operation of said siphon, substantially as described.

3. An apparatus for washing photographic negatives and prints comprising a tank, a pipe for supplying water to said tank, a funnel at the upper end of said pipe, an overflow pipe leading from said funnel, a valve for regulating the flow of water through said pipe for supplying water to said tank, a siphon adapted to discharge the water from said tank, said siphon having a bend of oval cross section between its legs and an opening in its shorter leg above the lower end thereof, substantially as described.

4. An apparatus for washing photographic negatives and prints comprising a tank, a pipe for supplying water to said tank, a funnel at the upper end of said pipe, an overflow pipe leading from said funnel, a valve for regulating the flow of water through the pipe for supplying water to said tank, a siphon adapted to discharge the water from said tank, said siphon having an opening in its shorter leg above the lower end thereof and a bend of oval cross section between its legs, and having also a

cutaway part at the rear and lower end of said shorter leg whereby the negatives and prints are prevented from interfering with the operation of said siphon, substantially 5 as described.

5. An apparatus for washing photographic negatives and prints comprising a tank, a pipe for supplying water to said tank, a funnel at the upper end of said pipe, 10 an overflow pipe leading from said funnel, a valve for regulating the flow of water through the pipe for supplying water to said tank, a siphon adapted to discharge the water from said tank, said siphon hav-

ing an opening in its shorter leg above the 15 lower end thereof and having also a cut-away part at the rear and lower end of said shorter leg whereby the negatives and prints are prevented from interfering with the operation of said siphon, substantially 20 as described.

In testimony whereof I have signed my name to this specification in the presence of two subscribing witnesses.
